UNITED STATES PATENT OFFICE

CLARENCE H. STEMMONS, OF KANSAS CITY, MISSOURI

DESIGN FOR A SHOE

Application filed January 11, 1933. Serial No. 46,790. Term of patent 3½ years.

To all whom it may concern:

Be it known that I, CLARENCE H. STEMMONS, a citizen of the United States, residing at Kansas City, Jackson County, Missouri, have invented a new, original, and ornamental Design for a Shoe, of which the following is a specification, reference being had to the accompanying drawing, forming a part thereof.

In the drawing:

I claim:

The ornamental design for a shoe as shown.
CLARENCE H. STEMMONS.
